UNITED STATES PATENT OFFICE.

DANIEL WARNER, OF TOLEDO, OHIO, ASSIGNOR TO GEORGE W. HEARTLEY,
OF SAME PLACE.

COMBINED POWER AND HAND PUNCH.

SPECIFICATION forming part of Letters Patent No. 415,286, dated November 19, 1889.

Application filed February 16, 1888. Serial No. 264,313. (No model.)

To all whom it may concern:

Be it known that I, DANIEL WARNER, a citizen of the United States, residing at Toledo, in the county of Lucas and State of Ohio, have invented certain new and useful Improvements in Combined Power and Hand Punches; and I do hereby declare that the following is a full, clear, and exact description of the invention, which will enable others skilled in the art to which it appertains to make and use the same, reference being had to the accompanying drawings, and to the letters of reference marked thereon, which form part of this specification.

15 My invention relates to a combined power and hand punch, and has for its object to construct a machine for punching metal that shall automatically unclutch, and that can be readily clutched when it is desired to use the 20 punch, and to also provide convenient means by which the punch may be raised or lowered by hand for the purpose of centering the same previous to punching by power.

Another object is to attach a stripper capable of lateral movement to allow of punching 25 metal of irregular shape.

A further object is to actuate the plunger to which the punch is attached by means of an eccentric upon a main shaft through the 30 medium of a link articulated with the plunger by a ball-and-socket joint, thereby obviating the possibility of the same becoming cramped in the ways.

Another object is to provide a movable and 35 reversible die-plate, thereby allowing the die to be moved to suit the convenience of the metal to be punched.

Another object is to construct a clutch with the operative parts controlled by mechanism 40 within the power-shaft, a still further object being to arrange a hand-power attachment that shall work effectually when it is not desired to use other power, another object being to provide means for automatically supplying oil to the chuck by feeding the same 45 through a perforation in the plunger.

The invention consists in the parts and combination of parts hereinafter described and claimed.

50 In the drawings, Figure 1 is a perspective

view of a power-punch with the bevel-gear and lever-stud employed in converting the same into a hand-punch, the whole being mounted upon a stand, which is also arranged to serve as a cabinet for tools. Fig. 2 is a detail view of a quadrant-gear and lever-socket employed in manipulating the punch by hand. Fig. 3 is a sectional elevation of the device, taken through a portion of the counter-shaft to illustrate the clutch mechanism 55 and eccentric. Fig. 4 is a detail view showing a front elevation of the reciprocating plunger, also showing a portion of the punch-chuck connected therewith and the link-connection of the same with the eccentric upon 60 the counter-shaft. Fig. 5 is an elevation of a portion of a power-punch with the hand-power attachment in operative position.

A designates the stand, preferably formed with shelled compartments on two sides, 70 which are closed by doors A', and with shelves A'' upon the upper end, the whole being arranged for convenience of disposing tools.

B designates the metal frame of the drill; B', the power-shaft receiving motion from pulley 75 B'', and communicating motion to counter-shaft E, journaled in frame B, through the medium of pinion C on shaft B' and gear D, loosely mounted upon the counter-shaft. Gear D bears at one side against a boss upon 80 frame B, and is held from longitudinal movement upon the shaft in an opposite direction by means of a right-angled keeper D'', secured at one end to the frame, the opposite depending end being inserted in a groove in 85 the hub of gear D. The opposite side of gear D is formed with clutch-faces D', which engage with corresponding clutch-faces upon a movable clutch-section F, secured to shaft E by a spline adapted to allow longitudinal 90 movement of the same upon the shaft. Section F is held normally out of engagement with the clutch-section upon gear D by means of a spring C within a cored-out portion of shaft E, formed by drilling a hole in the end 95 of said shaft, of a diameter and length to accommodate a spring of the dimensions required. The hole in the shaft is continued from this point preferably with a less diameter, thereby forming a shoulder, against 100

which the inner end of the spring rests, and extends for fully one-half the length of the shaft.

5 G' is a rod connected with clutch-section F and extending within hole G, and is connected to a movable collar H upon shaft E by means of a pin passing through the collar and an elongated slot in the shaft, the pin also passing through rod G'. Collar H is moved longitudinally upon shaft E by means of a treadle K and its connection through rod I' with a bell-crank lever I, having one arm resting within a peripheral groove H' in said collar, by which means the clutch-sections are thrown 10 into engagement to revolve shaft E.

15 E' is an eccentric upon shaft E near the end thereof, the shaft having a reduced end portion journaled in the main frame, with an extension to which is attached a hand-wheel 20 E'', by which shaft E can be revolved by hand, for a purpose hereinafter stated.

25 L' designates a plunger reciprocating in ways formed in the drill-frame and receiving motion through the medium of link L, the upper end of which is journaled upon eccentric E', and the lower end being connected to the plunger by a ball L'', working in a socket formed in the plunger, by which means the plunger may have an easy movement, without possibility of being cramped in the ways. The lower end of the plunger is provided with means for attaching any preferred form of chuck for holding the punch.

30 To provide for automatically supplying oil to the punch to prevent heating of the same, there is a chamber V formed in the plunger, having a passage U, which communicates with an opening U' in the side of the frame, by which oil is admitted to chamber V; and by 35 means of a passage leading from chamber V to the opening W in the plunger, in which the chuck is held, oil may be fed through grooves W' in the chuck-holder to the punch; or, if desired, the chuck may have a central perforation by which to lead oil to the punch.

40 O designates the die-bar, which is of oblong rectangular form, and which is provided on one or more of its sides with die-plates P. These die-plates P are of different sizes and 45 shapes to accord with different classes of work to be produced by the machine, so that the same bar is adapted for a great variety of work, and, as will presently appear, may be readily adjusted for the different classes of 50 work to be performed.

55 An opening or socket extends longitudinally through the base of the frame, and into the top and sides of said base are tapped set-screws O', as is best shown in Figs. 3 and 4. The die-bar O is inserted lengthwise into the opening or socket in the base, and is held in its required position by the set-screws O'. The bar O is inserted to a greater or less extent within the socket, according to the particular die-plate to be brought into operative 60 position beneath the punch, and after one die-plate has been used the die-bar may be

turned sidewise or reversed longitudinally to bring any one of the other die-plates into operative position, as desired, the set-screws O' being simply first loosened and then tightened up again after the bar has been properly adjusted. Thus it will be seen that the same die-bar may be used for a great variety of work, and that the inconvenience arising 75 from the use of a great number of die-bars is avoided.

80 M is a vertical hanger suspended from the frame, and having a stripper N pivotally secured thereto by a bolt N', passing through the stripper and hanger, by which means the lower portion of the stripper can move laterally with relation to the hanger, the bolt N' being the pivot upon which the stripper turns. This movement allows the stripper to swing 85 to one side or the other of the hanger. Should there be an irregularity in the metal being punched, a stud M' upon the hanger enters a slot upon the back of the stripper and tends to steady the same in its lateral movement. 90

95 So far the device has been described as a power-punch, in which power is transmitted by belt to pulley B, and through pinion C to gear D, the clutch-sections being disengaged by means of spring G, preferably coiled around rod G', counter-shaft E remaining stationary. The metal to be punched is placed upon die-plate C, and, if desired, the punch may be brought to bear upon the metal previous to punching, in order to ascertain if the metal 100 is in proper position, by means of hand-wheel E'', which upon being revolved turns shaft E and eccentric E', bringing the punch down to the metal. If desired, the punch may be raised by turning the shaft to bring the eccentric to its highest point, or power may be applied with the punch resting upon the metal. To apply the power, treadle K is depressed, throwing the clutch-sections D' and 105 F into engagement, and the punch is depressed, as described.

110 To insure an unvarying feed of lubricant to the punch to avoid heating of the same, oil is poured through perforations U' and finds its way to the chuck through passages U 115 and W'.

120 Q designates a bevel-gear rigidly keyed to shaft E, and with segmental gear S, fulcrumed upon stud R, constitutes a hand-power attachment to the punch, gear S being operated by a handle S'', attached to a socket-piece T, formed integral with said gear.

125 To operate the punch by hand-power, the handle S'' is secured to the socket portion T of segmental gear S. Said gear is fulcrumed upon stud R, with the segmental gear in engagement with bevel-gear Q upon shaft E. To raise or depress the punch, handle S'' is reciprocated, causing segmental gear S to give a sufficient rotative movement to shaft E to cause eccentric E' to move to its highest or lowest point, thereby reciprocating the plunger and punch connected therewith.

130 The device is compact, consists of few

parts, and is easily manipulated by the operator.

What I claim, and desire to secure by Letters Patent, is—

5 1. In a punching-machine, a power-shaft, a pinion keyed thereon, a counter-shaft, and a gear loosely journaled thereon and held from longitudinal movement by a right-angled keeper attached to the punch-frame, and having an angled portion projecting into a groove in the hub of the gear, as and for the purpose set forth.

15 2. In a punching-machine, a counter-shaft and a gear loosely mounted thereon receiving motion from a power-shaft, in combination with a clutch-section having a longitudinal movement upon the counter-shaft and operated by means of a spring and rod within the counter-shaft, as and for the purpose set forth.

20 3. In combination with a shaft having a cylindrical bore, a clutch-section having a longitudinal movement upon the shaft, a gear loosely journaled upon the shaft and provided with a clutch-face, with a rod located within the bore connected to a shipper-collar and clutch-section, and a spring bearing against a portion of the shaft and the clutch-section, as and for the purpose set forth.

25 4. In a punching-machine, the combination, with a frame and ways formed in the same, of a plunger reciprocating in said ways and carrying a chuck, an opening or perforation in the ways, an oil-chamber located near the lower end of the plunger, a passage lead-

ing from the side of the plunger to the oil-chamber, and adapted to, while in operation, intermittently communicate with the opening in the ways, and a passage leading from the chamber to the chuck held within the plunger, substantially as described.

40

5. In a punching-machine, a frame and a hanger secured therein, in combination with a stripper pivoted upon the hanger to allow of lateral movement with relation to the hanger, as and for the purpose set forth.

45

6. In a combined power and hand punch, a counter-shaft, a bevel-gear keyed thereon, a segmental gear journaled upon the frame and engaging with the bevel-gear, and a lever for operating said segmental gear, as and for the purpose set forth.

50

7. In a punching-machine, the combination, with a frame provided with an opening through the base thereof, of a die-bar having interchangeable faces and carrying a plurality of non-aligning die-plates, and set-screws for holding the bar within the frame, whereby said die-bar is adapted to be moved longitudinally, reversed, or turned, substantially as and for the purpose described.

55

In testimony that I claim the foregoing as my own I hereby affix my signature in presence of two witnesses.

DANIEL WARNER.
